GLAZING BAR

Ralph W. Emerson, Chicago, and Stirling H. Harper, Wilmette, Ill.

Application April 3, 1931, Serial No. 527,490
Renewed June 14, 1934

5 Claims. (Cl. 108—16)

The present invention relates to glazing bars for buildings and has particular reference to glazing bars of extruded aluminum.

An object of the present invention is to provide glazing bars of aluminum.

A primary object of the present invention is to provide a new method of securing glass or other sheet material to glazing or other framing bars of structures or parts of structures built of metal or wood bars and sheet material, and further to provide bars of a new pattern suitable for such method of sheet material securement. The method and bar design, while utilizing new materials and new methods of manufacture and overcoming the difficulties experienced in previous methods, is so designed as to use the materials efficiently, to minimize need for expensive field operations and to substitute, insofar as possible, the better quality and greater economy of shop labor for the inexactness and high cost of field labor.

Among the difficulties encountered in previous methods of construction of this type may be mentioned deterioration of materials, leakage of weather from without and water of condensation from within, uncontrollable air leakage, excessive breakage of glass due to localized fixed or screwed fastenings, the difficulty of replacing sheet material, and the high cost of both construction and maintenance.

To provide against deterioration of materials and to aid in reducing the manufacturing cost the metal parts of the present invention are designed to be made from aluminum or if desired from bronze or other non-deteriorating metals, by rolling, die drawing, stamping, extruding or other similar methods whereby low cost of production in large volumes of accurately formed especially designed parts is secured.

There is everywhere a growing demand for light weight simply and economically constructed enclosing walls and roofs, which, occupying a minimum of space, are still so designed and constructed as to overcome all previous difficulties and be attractive and clean in appearance with the design of the various parts expressing the function of the same. The constructional features of such parts must be adapted either to glazing or to closing in with thin sheet material. Where glazed such structures must offer the minimum of obstruction to light from various directions.

Structures to which the type of the construction of the present invention might be applied are generally built with a skeleton framework

of which the supporting members for the bars of the present invention would be the purlins of roofs or walls or the wall spandrel beams.

Another and still further object of the invention is to provide metallic glazing bars and novel anchoring means for securing said bars to the frame structure without the use of rivets, bolts, or like fastening means.

The new method of the present invention for securing glass or other sheet material to glazing or framing bars consists primarily in the use of preformed spring covers so designed of spring material whereby the covers may be easily snapped over or easily removed at will from suitably formed and cooperating heads of glazing or framing bars and to retain the covers in engagement with said bars with continuous spring pressure thus holding the covers in position. The covers of the present invention are not crimped or bent but rely for the spring action due to the construction of the covers, for retaining the same in applied position.

The above, other, and further objects of the invention will be apparent from the following description, accompanying drawings, and appended claims.

Embodiments of the invention are illustrated in the accompanying drawings and the views thereof are as follows:

Figure 1 is an isometric view of a bar made in accordance with the present invention showing the section of the bar.

Figure 2 is a fragmental enlarged partial sectional view showing one means for securing glazing bars of the present invention to the building structure, and also one means for supporting cross glazing bars.

Figure 3 is an enlarged vertical transverse sectional view taken through a bar such as that of Figure 1 showing the same installed in a building and the preferred manner of supporting the glass.

Figure 4 is a fragmental isometric view of a modified form of bar with a glass ledge and gutter on but one side of the same.

Figure 5 is an enlarged fragmental sectional view showing the glazing bar of the present invention as the same appears when mounted along a truss adjacent the junction of that truss with a truss forming a purlin.

Figure 6 is a fragmental isometric view of a bar of modified section.

Figure 7 is an isometric view of a combined glazing bar and rafter or frame member integrally formed.

Figure 8 is a fragmental view with a glazing bar in section and showing the manner of support of the bars of Figure 6 with the glazing bar of Figures 1 and 3.

5 Figure 9 is a fragmental top plan view of a roof constructed with bars of the present invention.

10 Figure 10 is an enlarged fragmental sectional view of a portion of a roof constructed with bars 10 of the present invention.

15 The bars of the present invention may be used with any type of building or roof construction, steel, wood, or otherwise wherein the rafters or trusses are connected at intervals by purlins preferably of channel or angle members.

20 The roof bars or glazing bars are arranged along the rafters or trusses running from the peak of the roof down to the sides of the building or like structure and also disposed at intervals between the trusses or rafters or purlins which run lengthwise of the building. The glazing bars may extend to the ground line if desired.

25 The glazing bars illustrated in Figures 1, 3, 5 and 8 are made of extruded aluminum forming bulbous heads 1, webs 2, bottom flanges 3 with inclined side margins 4 and ledges 5 intermediate the heads and the bottom flanges.

30 The ledges 5 are formed on each side of the webs 2 except in such instances where it is desired to support glass panes along one side only of such bars in which event the base and ledge on one side of the webs are omitted as illustrated in Figure 4.

35 The upturned side margins 4 cooperate with the base flange 3 to form gutters on each side of the webs 2. Preferably the upper faces of the ledges 5 are corrugated to retain the bedding for the glass panes on the ledges.

40 The bar as illustrated in Figures 1, 3, 5, and 8 is so fashioned as to distribute the metal symmetrically about vertical and horizontal axes of the section of the bar thus affording sufficient strength and rigidity.

45 The bar illustrated in Figure 1 is full size and is the size actually used as glazing bars for buildings.

The rafters or trusses may be of any design whatsoever and of wood, steel, or other material.

50 Figure 5 illustrates a glazing bar A secured along a truss formed in the present instance with angles 6 and 7 and an intervening plate 52 on the upper edges of which the bar A rests.

55 At intervals in the length of the truss or rafter formed by the angles 6 and 7 purlins 8 are fastened in any desired manner such for instance by angle plates at the connections. The purlins run lengthwise of the building or like structure, that is, perpendicularly to the trusses or rafters.

60 The glazing bars A fastened to the purlins 8 intermediate the rafters or trusses are secured thereto by clips as illustrated in Figures 2 and 3.

65 Each clip B comprises a body 9 having an end 10 spaced from the body at one end thereof and a shoulder 11 at the other end. The end 10 extends inwardly from the adjacent end of the body B and is disposed to underlie the upper flange 12 of a purlin 8. The clips B are fastened to the flanges 12 of the purlins 8 by hooking the end 10 under the under surface of the upper flange 70 and snapping the shoulder 11 down over the web of the purlin. The clip B is preferably of spring metal and forms tight connection with the purlins. The clip is provided with an inwardly directed portion 13 for bearing against the adjacent face of the web of the bar A to limit inward

5 movement of the clip with respect to such bar. The length of the portion 13 is such that the inner surface of the end member and also of the body of the clip bears against the adjacent upturned edge 4 and cannot be driven against such upturned edge with sufficient force to distort or break the same. Two clips B are generally utilized to secure one of the bars A to a purlin between trusses or rafters. The two clips so employed are secured together by a bolt 14 passing through suitably disposed apertures in the clips which bolt is fastened by means of a nut 15.

10 When the glazing bars A are extruded a groove 17 is formed in each side of the web 2 beneath the ledge 5 as a drill centering groove so that the web may be drilled wherever it is desired to install clips B and the bolts 14. The grooves 17 serve to center the drill point while making such bolt holes.

15 The arrangement shown in Figure 3 is that looking at the left side of Figure 2 and is somewhat enlarged.

20 Figure 3 illustrates one manner of supporting glass panes C by the glazing bars of the present invention. A strip of plastic material 18 is laid along the ledge 5 on each side of the web 2 of the bar and another strip 19 of plastic material is laid against the web 2 adjacent the ledges 5. The panes C are then placed on top of the plastic strips 18 whereupon plastic strips 20 are laid along the top edge of the pane adjacent the glazing bars.

25 The clips or covers D are formed of uniform cross section and symmetrically about a vertical plane passing through the covers from end to end. The covers have a central curved portion 35 54 which forms the top of the cover and with the intermediate portion on each side turned forming bar engaging legs 24. The sides of the cover extend downwardly from the legs 24 and have the lower portions outturned forming seats 30 22 and 21 for bearing against the sheet material such as glass which is to be maintained in proper 35 relation with respect to the framing bars A. The undercut grooves 23 receive the legs 24 of the 40 clips or covers D with the grooves serving as a continuous fulcrum to transmit a portion of the internal spring action of the curved part 54 which acts to bend the legs 24 towards each other and thus hold the cover onto the bar with spring action.

45 The top 54 of the cover, when the cover is in applied position, is out of contact with the bar A thus providing an insulating space between the cover and the bar. The form of the seat or flanges 21 and 22 is such that any resultant of outward force exerted on the sheet material combined with the forces created by the internal 50 spring action of the legs 24 and the top 54 serves to increase the engagement of the legs 24 with the grooves 23 thus aiding in securely retaining the cover on the supporting bar and in turn retaining the sheet material B in position.

55 The covers D are preferably made in lengths equal to the lengths of the sheet material with slightly deformed overlapping portions at the ends of the covers to insure continuously uniform retaining pressure against the sheet material.

60 Preferably the spring covers D are made in lengths equal to the lengths of the sheet material B with slightly deformed overlapping portions at the ends of the cover to insure continuously uniform pressure against the sheet material for retaining it in position.

It is obvious that the unit pressure per inch of length of cover on either side is thus required to be only one twenty-fourth of the amount of pressure which would be required were retaining fastenings spaced twenty-four inches apart. It is by this improvement that is reduction of the unit pressure and continuity of uniform pressure that the present invention eliminates breakage of sheet material.

Assisting in the elimination of breakage of the sheet material such as glass is the use of the cushioning or bedding strips 20 interposed along the margins of the glass sheets where the same are supported in the frame structure, and the choice of the preferred metal, aluminum, which has mechanical properties substantially the same as of glass.

The covers D are easily applied over the heads of the supporting bars by pressure applied along the tops 54 of the covers and may be easily removed for replacing broken glass or the like by beginning at one end of a cover and spreading the skirt or pressing the curved top 54 toward the head of the bar thus freeing the engaging legs 24 from engagement with the undercut grooves 23 in the bars.

No fastening means of any character are employed to maintain the covers in position as the spring pressure of the covers against the bars is sufficient to retain the same under all conditions of service.

The undersides of the heads 1 of the glazing bars are undercut as at 23 to receive the inturned portions 24 of the clips D.

The glazing bar E of Figure 4 comprises a head 1a, a web 2a, a bottom flange 25, an upturned side marginal flange 26, and a ledge 27. The bottom flange 25, side flange 26, and glass ledge 27 are formed on one side only of the web 2a for use where it is desired to support the glass along one side only of such glazing bar such for instance as illustrated in Figure 10.

A groove 53 is cut in the head 1a to receive an end of a clip D' for securing the clip to the bar.

Figure 6 illustrates an extruded aluminum glazing bar which is utilized to extend along the roof in register with the purlins and consists of a top flange 28, a web 29, a glass supporting ledge 30 on one side of the web and another glass supporting ledge 31 on the opposite side of the web. A gutter 32 is formed by a portion 33 spaced below the ledges 30 and 31 on one side of the bar. This bar F is illustrated in Figures 2 and 10. The height of the bar F that is from the flange 28 to the lower surface of the lower portion 33 forming the gutter is less than the overall height of the bars A and E.

Figure 8 illustrates an assembly of a glazing bar A and two glazing bars F. It will be noted that the lower portions 33 of the bars F rest on top of the side flanges 4 of the bar A thus spacing the bars F above the truss or rafter carrying the glazing bars A. In this arrangement the gutters 32 of the glazing bars F discharge into the gutters formed in the bars A whereby condensation may be carried away to eaves or outside gutters as desired.

In Figures 9 and 10 showing fragmental portions of a roof construction utilizing the glazing bars of the present invention a ridge 34 is supported on a separator plate 35 suitably attached to the roof framework. Glazing bars G are provided for cooperating with the separator plates 35 and the ridge 34. The ridge 34 has converging portion 36, vertical portions 37 therebelow,

out turned flanges 38 and upwardly inclined side flanges 39. The portions 37 and the flanges 38 and 39 forming gutters 40. The glazing bars 6 are suitably secured to the inclined portions 36 and as shown are arranged in back to back relation.

Each glazing bar G is provided with a laterally extending lug 42 to receive panes of glass suitably seated thereon by plastic strips of the character and arrangement as described with reference to Figure 3. Clips D' cooperating with the heads 41 of the glazing bars G retain the glass panes against the lugs or shelves 42 in the same manner as described with the preceding figures.

The heads 41 are grooved to receive the in-turned portions 54 of the clips D'.

The portion of roof illustrated in Figure 10 is inclined with glazing bars A extending along the rafters or trusses downwardly from the ridge 34. Purlins 8 are provided on which similar glazing bars A rest.

Extending lengthwise of the roof, that is, parallel to the separator plate 35 and overlying the several purlins 8 are glazing bars F arranged with the gutters 32 thereof opening upwardly. These bars F rest on the upturned flanges 4 of the glazing bars A and also on the clips 9 thus spacing the lower portions 33 of the bars F above the upper flanges of the purlins 8. Any condensation accumulating in the gutters 32 of the glazing bars F passes into the gutters of the bars A at the ends of the bars F so that such condensation may pass downwardly to suitable eaves for disposal. The glass panes are supported on the ledges or shelves 30 and 31 of the glazing bars F being spaced therefrom by, plastic strips 43 with upstanding strips against the adjacent edges of the panes. It will be observed that the upper edge of the pane is inserted between the flange 28 and the ledge 30 so that access of rain, snow, and the like is prevented whereas the lower margin of the pane is supported on the ledge 31. The provision of the plastic strip 43 and the end strip 44 prevent seepage of rain and the like past the panes.

The clips D and D' cooperating with the glazing bars A may be made as long as desired that is as long as the several bars A so as to have no opening through the same. Although for convenience in replacing broken panes of glass the clips are made in length the distance from one purlin to the next as preferred.

The glazing bars A, E, F, and G may be bent to provide a roof structure of any desired shape.

These bars may be extruded at the mill and supplied in any standard lengths such as 8, 10, 12, 14, 20 feet and the like and cut to proper lengths on the job. The bars may also be bent on the job to provide the curvature desired.

Figure 5 illustrates one manner of tying glazing bars A when the same are mounted along the truss or rafter of the roof structure.

Clips 45 having upstanding body portions are provided. The clips 45 have inwardly extending portions 46 for engaging against the web 2 of the bars A and limiting inward movement of the clips with respect to the bars. The clips 45 are provided with extensions 47 which extend away from the body portions thereof in a direction opposite to the portions 46. The extensions 47 are provided with shoulders 48 for engaging against the web of a purlin 8 and inturned ends 49 for hooking over the upper flange of the purlin similar to the arm 10 of the clip B illustrated in

Figure 2. The clips 45 are arranged one on each side of a glazing bar A where the same is disposed along the truss or rafter and are held in position by a bolt 50 passing through apertures 5 in the clips and also in the web 2 of the bar A.

It will be observed that the bars A are designed so that median lines both vertical and horizontal are drawn through a section of the same, show an even disposition of metal above and below and also on each side of such median lines. This structure provides bars which are strong and rigid and serviceable.

Sometimes in the erection of small greenhouses or like structures it is desired to make the glazing bar integral with the rafter or plate. Figure 7 illustrates a glazing bar and rafter extruded to form an integral structural member. The rafter 51 is shown as rectangular and integrally formed with the glazing bar A' which otherwise is constructed exactly in accordance with the bars A heretofore described. The combination bar A' and rafter 51 may also be bent to provide a roof of desired shape.

It will be observed that this invention provides glazing bars which are light, strong, and which are made of metal which is not subject to deterioration by weather conditions. Such bars are easily bent to provide structures of any desired style and shape and also are light enough to be readily installed without excessive labor. The use of clips for attaching these bars to the structure is beneficial in that the clips may be arranged along the length of the bars as desired and secured thereto in selected positions by bolts passing through the webs of the bars, the bolt holes being formed at desired points by the erector who readily centers his drill in the drill notch provided for this purpose. The clips are spring clips which grip the purlins tightly to prevent displacement 40 of the glazing bars in service.

The use of glazing bars in the present invention may be readily understood and also the advantage of the bars in the present invention may be understood. The bars of this invention may be manufactured in any standard lengths as desired, transported to the place of use and there cut to proper lengths whatever the lengths may be and also shaped to proper curvature thus reducing the labor cost incidental to the erection of 50 greenhouses and like structures. The glazing bars being of metal are stronger than those made of wood and at the same time are of much smaller cross sectional area so as to reduce to a minimum the shadow effect created by the glazing bars. 55 These bars being made of aluminum suffer no ill effects from weather conditions and consequently do not have to be repaired or painted.

Figure 1 illustrates full size of the bars of type A whereupon it may be readily understood and 60 observed that such bars reduce to a minimum the shadow effect created by reason of the use of the same. It will be observed also that bars of the type A are much smaller than wooden bars would have to be for supporting glass of the 65 same size and area.

It may be readily understood that special shapes of these bars may be readily extruded as the cost of extruding dies is comparatively small compared with the waste of lumber when bars 70 are made of wood.

The glazing bars of the present invention may be used for any and every kind or type of glazing such as roofs, walls, partitions, and the like.

The glazing bars of the present invention can 75 be used to support the glass panes in an over-

lapped position as well as in abutting position such as is illustrated in the drawings. In the event the glass panes are overlapped such overlap would be approximately one-quarter of an inch at every joint, in which event the attaching clips B would be as long as a pane and overlap at the ends where the panes overlap.

The glazing bar of the present invention is desired like a beam for the equalization of the compression and tension stresses set up when loaded. The metal is evenly distributed for such purposes. The use of spring clips for maintaining the panes in position on the glazing strips serves at all times to wedge the panes against the embedded mastic thus assuring a weather- 15 proof joint at the glazed portion.

The mastic which is proposed to be employed in glazing with the bars of the present invention is made up in strips or rolls so as to be readily unrolled or set along a glazing ledge or shelf thus reducing cost of application of such mastic and doing away with the necessity of using putty as must be done with mastic or equivalent substances, in other forms than rolled or in strips.

The mastic or embedding material utilized 25 along the edges of the glass pane is preferably of an asphaltic compound with asbestos or similar fiber incorporated therein and is made in the manner of a preformed strip or tape of sectional contour conforming to the glazing bars and the 30 spring cover of the invention. The tape is preferably supplied to the job in roll form with a separating strip of paper between the layers so that the tape may be unrolled along the margins of the glass or other sheet material employed to 35 expedite the application of the tape to the material. The use of the bedding material in tape form enhances the appearance of the finished structure and not being necessarily injured in application or removal may be reused if occasion 40 arise.

The glass supporting ledges of the bars of the present invention are provided with a multiplicity of grooves and projections 55 and 56 respectively which cooperate with and retain in proper position the mastic tape material.

It has been found in practice that glass supported on steel bars breaks more readily than when supported on wood. The natural characteristics of glass and aluminum are similar and less breakage of glass should occur with aluminum than with wood. The modulus of elasticity of aluminum and glass is approximately the same whereas for steel it is three times that of glass or aluminum.

The size, shape and arrangement of the illustrated form of bars are designed for strain where the bar is supported at intervals of five to six feet, thus doing away with the intermediate support necessary when wooden bars are employed.

The protuberances 55 are provided for the purpose of urging the mastic downwardly against the pane when the clips are applied to the bars for retaining the pane on the bars.

The separator plates 35 illustrated in Figure 10 are usually short plates disposed at intervals in the length of the ridge 34 and are not continuous with the ridge.

The present bar was developed for economy of labor in the field and designed so that as much work as possible might be done in the shop thus reducing the field labor to a minimum.

All the erectors have to do in applying glazing bars of the present invention is cut the same to proper length which may be readily done with a 75

hand saw, apply the clips for fastening the bars to the purlins or trusses and drill the webs wherever any of the bolts 14 and 15 are to be inserted. The provision of the notches 17 in the webs of the bars serve as centering notches for the drill so that the erector does not have to ascertain the correct place for the hole and use a prick punch for indicating the place to be drilled. He ascertains the correct position for the bolt and then places his drill in the groove and drills a hole for the bolt.

Referring to Figure 10 where the bars F are shown as supported on the upturned flanges 4 of the bars A, it will be observed that the bars F are illustrated in this manner for clarity of understanding whereas when it comes to practical installation, the bars F are mounted on the clips 9 as illustrated in Figure 2. Mounting the bars F in the manner illustrated in Figure 2, especially in a sloping roof the clips 9 serve to prevent movement of the bars F downwardly as it will be noted these bars rest against shoulders formed in the clips thus preventing gravitational movement downwardly.

The clips of the present invention engage the sides of the glazing bars with uniform and continuous pinching action from end to end, with skirts or seats which rest against the sheet material, consequently exerts continuous pressure against such sheets. This provision of continuity of pressure along the sheet material prevents fractures and breakage such as are found in clips or attaching means of different construction.

The invention has been described herein more or less precisely as to details yet it is to be understood that the invention is not to be limited thereby as changes may be made in the arrangements and proportions of parts and equivalents may be substituted without departing from the spirit and scope of the invention.

The invention is claimed as follows:

1. Means for securing sheet material such as glass to framing or glazing bars, said means comprising spring sheet metal covers of uniform section and having substantially arcuate circular central portions with the sides thereof inturned and then down and outturned, the inturned portions constituting engaging legs and the outturned portions constituting seats for contacting the sheet material, the engaging legs contacting the bars with substantially line contact, the covers otherwise being out of contact with the bars, the central curved portions of said covers being put under strain when said covers are applied to the bars thereby tending to urge said legs together, such action increasing the engagement of the covers with the bars.

2. Means for securing sheet material such as glass or the like to framing or glazing bars, including a spring sheet metal cover member engageable with a framing bar with spring action for securing sheet material to said bar, a fram-

ing bar having lateral grooves along the sides thereof, said cover having in the height thereof inwardly directed portions constituting legs for engaging said grooves when a cover is applied to a bar, said cover otherwise being out of contact with said bar, the construction of the cover being such that the portion connecting said legs is strained when the cover is in applied position and the strain so imposed being effective to cause said legs to engage said grooves with spring action.

3. Means for securing sheet material such as glass or the like to framing or glazing bars, including a spring sheet metal cover member engageable with a framing bar with spring action for securing sheet material to said bar, a framing bar having undercuts along the sides thereof, said cover having in the height thereof inwardly and upwardly directed inturned portions constituting legs for engaging said undercuts when said cover is applied to said bar, the portions of said cover below said legs being outturned constituting seats for contacting sheet material, said last named portions being compressed when a cover is applied over a bar and against the sheet material, such compression tending to increase the engagement of said legs with said undercuts.

4. Means for securing sheet material such as glass or the like to framing or glazing bars, including a spring sheet metal cover member engageable with a framing bar with spring action for securing sheet material to said bar, said cover comprising a central connecting part having in-turned portions along the sides thereof constituting legs for engaging a bar, a glazing bar having grooves along the sides thereof engageable by said legs, the connecting portion of said cover acting with spring action to force said legs into engagement with said bar grooves when a cover is in applied position.

5. Means for securing sheet material such as glass or the like to framing or glazing bars, including a spring sheet metal cover member engageable with a framing bar with spring action for securing sheet material to said bar, said cover having in the length thereof inwardly and outwardly directed inturned portions constituting legs, a framing bar having undercut portions along its sides, the legs of said cover being engageable with said undercuts when a cover is applied to a bar, the intermediate portion of said cover connecting said legs acting with spring action to squeeze said legs into engagement with said undercuts, portions of said cover below said legs being outturned constituting seats for engaging sheet material, said last named portions being compressed when a cover is applied over a bar and against sheet material, such compression tending to increase the spring engagement of said legs with said undercuts.
